UNITED STATES PATENT OFFICE.

SYLVESTER HURLBERT JANSEN, OF BUFFALO, NEW YORK; EMILY J. JANSEN
EXECUTRIX OF SAID SYLVESTER HURLBERT JANSEN, DECEASED.

CAR-RIGGING OR DRAFT APPLIANCE FOR RAILWAY-CARS.

SPECIFICATION forming part of Letters Patent No. 708,481, dated September 2, 1902.

Application filed November 10, 1899. Serial No. 736,556. (No model.)

To all whom it may concern:

Be it known that I, SYLVESTER HURLBERT JANSEN, a citizen of the United States, residing at the city of Buffalo, county of Erie, and State of New York, have invented a new and useful Car-Rigging or Draft Appliance for Railway-Cars, not known or used, to my knowledge or belief, by others before my invention with my consent or allowance, of which the following is a specification.

My invention relates to improvements in the draft appliances of railway-cars.

One object of my invention is to simplify and improve the construction of the draft-yoke and the draft-plates on which the follower-plates are guided; with a view of increasing the strength of these parts, facilitating the assemblage of the various members of the draft-rigging, and reducing the cost of the rigging.

Additional objects of my invention are to provide simple means for preventing buckling of the draft and buffer springs and to tie the draft-plates together in such a manner that any lateral strains received by either of the same are equally distributed between both, thereby increasing the strength and rigidity of the plates and rendering the same less liable to work loose.

In the accompanying drawings, consisting of two sheets, Figure 1 is a vertical longitudinal section of the improved rigging and the adjacent portion of a car-body. Fig. 2 is a sectional top plan view thereof. Fig. 3 is a cross-section in line III III, Fig. 1. Fig. 4 is a perspective view of one of the draft-plates, the adjacent draft-timber being indicated by dotted lines. Fig. 5 is a top plan view of the draft-yoke. Fig. 6 is a side view of the same. Fig. 7 is a top plan view of the tie-frame of the draft-plates. Fig. 8 is a transverse section thereof in line VIII VIII, Fig. 7.

In the drawings corresponding parts are designated by similar reference-figures.

1 designates the end sill of the car-body, 2 the center sills, and 3 the draft-timbers, secured to the under side of the center sills.

4 is the draw-bar, the front portion of which is supported by the usual carry-iron 5, and 6 is the draft yoke or loop, secured at its front and to the rear end of the draw-bar, prefer-

ably by vertical rivets 7, which pass through the upper and lower members of the yoke and the draw-bar and lips 8, formed at the front ends of said yoke members and interlocking with shoulders of the draw-bar, as shown in Fig. 1. The yoke is provided between its ends with an upright integral web or cross-piece 9 and is stiffened by longitudinal ribs or flanges 10.

Located in the front pocket or compartment of the draft-yoke 6 are a pair of follower-plates 11 and 12, between which the springs 13 and 14 are interposed, and located in the rear pocket or compartment of the yoke are a pair of similar follower-plates 15 and 16, between which the springs 17 and 18 are arranged. The front follower-plate 11 is adapted to abut against the rear end of the draw-bar and the rear follower-plate 16 against the closed rear end of the draft-yoke, while the intermediate follower-plates 12 and 15 abut against opposite sides of the web or cross-piece 9 of the yoke, as shown in Figs. 1 and 2.

19 19 designate the metallic draft plates or beams, secured to the inner sides of the draft-timbers and forming, with yoke 6, a housing, which incloses the draft and buffer springs and their follower-plates. As shown in Figs. 2 and 4, the inner sides of the draft-timbers are mortised to receive the draft-plates and confine them against longitudinal displacement. The plates are firmly secured to these timbers by horizontal bolts or rivets 20 and by vertical bolts or rivets 21, which pass through the draft-timbers and through longitudinal flanges 22, which project outwardly from the lower edges of the draft-plates and are preferably seated in recesses formed in the under sides of the draft-timbers to form a flush joint, as shown in Fig. 3. By this construction the draft-plates are rigidly fastened to the draft-timbers. Formed in the faces of the opposing draft-plates 19 are pockets or recesses 23, which receive and guide the laterally-projecting portions of the follower-plates 11, 12, 15, and 16, as shown in Fig. 2. Projecting inwardly from the faces of the draft-plates about midway between the abutments 24, which form the ends of the pockets 23, are bosses or projections 25, between which the front draft and buffer springs

13 and 14 are guided as the draw-bar moves in and out and which confine these springs against sidewise displacement, and thereby prevent buckling of the same. The bosses or 5 projections 25 each comprise parallel end plates 25^a, connected by a face-plate. As shown in Figs. 3 and 4, each draft-plate is formed near its top with an inwardly-extending longitudinal flange 26, which hold the following 10 lower-plates against upward displacement. The follower-plates rest upon the longitudinal bars or beams 27, which close the lower ends of the pockets 23 and which are secured to the lower ends or under sides of the abutments or bosses 24 of the draft-plates by vertical bolts 28 passing through holes 29, formed in side bosses. These bosses and the spring-confining bosses 25 are preferably made hollow, as shown, to lighten the same. For the 15 same reason the cross-piece 9 of the yoke is made hollow. The supporting-bars 27 are tied together at suitable intervals by cross-bars 30, which are arranged below the draft-yoke 6 and preferably cast integral with said bars. 20 25 These bars, while serving as a support for the follower-plates, at the same time form, with the cross-bars 30, a strong rectangular tie-frame, which rigidly binds the two draft-plates together. The lateral strains to which the 30 draft-plates and draft-timbers are subjected when the car passes around a curve are by this construction shared by both plates and timbers, thereby enabling these members to effectively resist such strains without working loose and requiring frequent repairs. 35

It will be observed that the two sets of springs 13, 14, 17, and 18 serve both as draft and buffer springs. When the draw-bar is pulled outward, the front follower-plates 11 40 and 15 of the two sets of springs abut against the front ends of their respective pockets in the draft-plates, while the rear follower-plates 12 and 16 approach said front plates and compress the springs. When the draw-bar is pushed inward, the rear follower-plates 12 and 16 abut against the rear ends of their respective pockets in the draft-plates, while the front follower-plates 11 and 15 approach said rear plates and compress the springs. 45 50 This duplex arrangement of the draft and buffer springs renders the appliance more effective in action.

By my improved construction of the draft-rigging the number of parts is reduced to a minimum, thus not only lessening the first cost of the device, but effecting a material

saving in the cost of repairs, which increases in proportion to the number of parts liable to work loose or get out of order. The parts can also be conveniently and quickly assembled. 60 This is accomplished by passing the draft-yoke, springs, and follower-plates upwardly between the draft-plates and then securing the tie and supporting frame 27 30 to the under side of the draft-plates. 65

A further advantage of my construction is that it dispenses with the usual tail-bolt, enabling the parts to be more easily assembled and avoiding weakening of the follower-plates by the openings which must be formed in 70 the same when a tail-bolt is employed.

I claim as my invention—

1. In combination with the draft-timbers of a car, draft-plates secured to the inner sides of the draft-timbers, vertically-disposed abutments formed on the inner faces of the draft-plates, bosses formed with the inner faces of the draft-plates intermediately the central and end abutments, said bosses comprising end plates connected by face-plates, 75 follower-plates adapted to travel between the abutments and the ends of the bosses, springs between the follower-plates, bearing against the faces of the bosses whereby said springs are guided, a yoke slidably between the draft-plates and having an intermediate cross-piece for confining the springs and followers and a draw-bar to which the yoke is attached as and for the purpose described. 80 85

2. In combination with the draft-timbers of a car, draft-plates secured to the inner sides of the draft-timbers, vertically-disposed abutments formed on the inner faces of the draft-plates intermediately the central and end abutments, said bosses comprising end 90 plates connected by face-plates, follower-plates adapted to travel between the abutments and the ends of the bosses, springs between the follower-plates, bearing against the faces of the bosses whereby said springs are 95 guided, a yoke slidably between the draft-plates and having an intermediate cross-piece for confining the springs and followers, a draw-bar to which the yoke is attached, bars bolted to the under edge of the draft-plates, cross-bars connecting the longitudinal bars whereby the draft-timbers are connected, as and for the purpose described. 100 105
